UNITED STATES PATENT OFFICE.

WILLIAM M. ADAIR, OF ALGANSEE, MICHIGAN.

DRAFT-EQUALIZER.

1,115,460.

Specification of Letters Patent. Patented Oct. 27, 1914.

Application filed June 17, 1914. Serial No. 845,644.

To all whom it may concern:

Be it known that I, WILLIAM M. ADAIR, a citizen of the United States, residing at Algansse, in the county of Branch and State 5 of Michigan, have invented certain new and useful Improvements in Draft-Equalizers; and I do hereby declare the following to be a full, clear, and exact description of the invention, such as will enable others skilled 10 in the art to which it appertains to make and use the same.

My invention refers to a draft equalizer and more particularly to the construction thereof.

15 The object of my invention is to provide an equalizer which will be strong, light and efficient at a moderate cost, as will be apparent in the following specification, reference being had to the accompanying drawings which are made a part of this application and in which,

Figure 1 is a view of my complete invention. Fig. 2 is a perspective view of an end of a brace showing the groove formed in 25 the end thereof and the end of the draft rod seated therein. Fig. 3 is a central longitudinal section of the same as indicated by dotted lines A—A in Fig. 2. Fig. 4 is a cross section of the end of a brace and draft 30 rod as indicated by dotted lines B—B in Fig. 2.

In the detailed description of my invention numerals will be used when referring to the drawings.

35 The same numeral being employed to indicate the same part throughout.

My invention consists of a draft-rod 1 formed preferably of a round iron or steel rod, having an eye 2 formed at its center, 40 its ends extending at an obtuse angle to each other, the extreme ends 3 are bent back inwardly upon themselves to form eyes 4 to receive the tug-hooks 5 or the clevis bolt 5^a, as the case may be, and extending a sufficient distance rearwardly from the eye 4 to permit of their being fastened to the body portion of the draft-rod 1 and the 45 ends of a brace 6 connecting the two ends of the draft-rod.

50 A brace 6 is formed preferably of wrought-iron pipe having its ends bent to meet the angle of the ends of the draft-rod, said end is also flattened and has a groove 8 formed in the outer side of the bent por-

tion thereof. The bent end of the said 55 brace is placed between the ends of the draft-rod to keep said ends in fixed spaced relation to each other. The end of the brace is fastened by a bolt or rivet 9 between the bent end of the draft-rod and the body portion 60 thereof, the latter portion being seated in the groove formed in the bent end of the brace 6, an iron ring 10 is placed around the draft-rod between the eye 2 and the body portion of said draft-rod to prevent the 65 spreading of the eye when a strain is put on the draft-rod.

The foregoing description and construction is of a member corresponding in use to a whiffletree. The identical construction 70 is employed to form a larger member which in use corresponds to a doubletree. The two being operatively connected by a clevis 11 in the usual way. Two of the former members and one of the latter comprising my 75 complete invention.

While I have described in the foregoing specifications and illustrated in the accompanying drawings the preferred construction and combination of parts deemed necessary in materializing my invention, I desire 80 it to be understood that I wish to comprehend in this application all substantial equivalents and substitutes which may be considered as falling fairly within the scope 85 of my invention and I do not therefore wish to be confined to the exact showing herein presented.

Believing that the construction, advantages and manner of using my invention 90 have thus been made clearly apparent, further description is deemed unnecessary.

Having thus fully described my invention, what I desire to secure by Letters Patent is:—

1. The combination with a brace member having its ends bent and flattened and a groove formed in the outer side of the bent portion, of a draft-rod having an eye formed in its central portion, its ends bent 100 to form eyes thereon and shaped to fit the bent end of the brace and provided with securing means for fastening the ends of the said draft-rod and brace together and a ring surrounding the draft-rod at its center 105 portion whereby the spreading of the eye is prevented.

2. The combination with a draft rod the

ends of which extend obliquely to each other and the extreme ends bent back to engage the ends of a brace, a brace having its ends flattened and bent and a groove formed in 5 the outer side of the bent portion to receive the bent end of the draft-rod; a rivet uniting the ends of these two members.

In testimony whereof I have signed my name to this specification in the presence of two subscribing witnesses.

WILLIAM M. ADAIR.
